GAME OR CHANCE DEVICE

George D. Gibson, Andover, Mass.

Application July 9, 1938, Serial No. 218,413

2 Claims. (Cl. 273—141)

This invention relates to a game or chance device, the primary object of the invention being to provide a device of this character including a plurality of stationary electrical contacts arranged in groups, and movable contacts cooperating with the stationary contacts in completing electrical circuits to distinctive lamp signal groups, causing certain lamps or groups of lamps to be lighted, whereby the score of the game may be determined.

Another object of the invention is to provide a device of this character wherein successful scoring of the game points depends largely on the skill of the players in rotating the control disk of the game.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a vertical sectional view through a game or chance device constructed in accordance with the invention.

Figure 2 is a plan view thereof.

Figure 3 is a transverse sectional view through the device.

Figure 4 is a bottom plan view of the device.

Figure 5 is a diagram illustrating the various circuits between a source of electricity supply, contact members and lamps.

Referring to the drawings in detail, the reference character 5 designates the base of the device, which is secured within the housing 6, by means of the screws 7.

The housing 6 is formed with an opening, through which the pipe 8 extends, the pipe 8 also extending through an opening formed in the base 5, where it is held in position by means of the nut 9. This pipe 8 extends an appreciable distance above the base 5, where it provides a support for the fixture 10 which is provided with lamp sockets 11, 12 and 13. Lamps 14 are positioned within the sockets, the lamps being preferably colored red, white and blue.

Bearings indicated by the reference character 15 are also secured to the base 5, and provide a support for the tubular shaft 16, which is shown as secured to the inner section of the bearing, 55 to move therewith. Secured to the upper end of

the tubular shaft, is a disk 17 which is provided with finger pieces 18 or knobs, whereby the disk may be rotated.

Mounted on the tubular shaft 16, and insulated therefrom by means of the tubular insulating member 19, is a tube 20, to which the arm 21 is secured, as by means of the bracket 22. This arm 21 is pivotally mounted on its bracket, at 23, the upper end of the arm being connected with the spring 24 that bears against the tube 20, to normally urge the lower end of the arm 21 downwardly.

As clearly shown by Figure 1 of the drawings, the lower end of the arm curves downwardly and laterally, where it provides a support for the rotary contact members 25, 26 and 27.

The reference character 28 designates a supporting plate constructed of insulating material, supported in spaced relation with the base 5, by means of the tubular post 29 and securing bolts 30.

Embedded in the supporting plate 28, are contact members 31, which are arranged in circular concentric paths, spaced apart as shown more clearly by Figure 3 of the drawings. These contact members are also arranged so that a group of three contact members spaced transversely of the plate, are provided, a pair of adjacent contact members arranged so that the two innermost contact members 26 and 27, will contact therewith, and a pair of contact members arranged so that the rotary contact members 25 and 26 will contact therewith simultaneously, and a group of contact members 31 so arranged that the innermost rotary contact member 21, and outermost contact member 25 will contact therewith, and single contact members arranged so that the contact members 25, 26 and 27 will contact therewith consecutively, as the arm 21 rotates, and the rotary contact members roll thereover.

The reference character 32 designates the main lead-in wire, which is connected with the house circuit embodying wires 33 and 34, the current passing through the wire 32 being controlled by the switch member 35. The wire 32 leads to the socket in which the white lamp 14 is positioned, the wire 36 leading from the socket 14, and connecting with the contact ring 37 which is in circuit with the contact members 31 of the innermost line of contact members 31.

The wire 38 connects with wire 32, and leads to the socket in which the blue lamp 14 is positioned. Wire 39 extends from the socket in which the blue lamp is positioned, and connects with the contact member 40 that is in circuit with the

contact member 31 of the outermost line of contact members. Leading from the wire 32, is a wire 41 that connects with the socket in which the red lamp 14 is positioned. The wire 42 also connects with the socket in which the red lamp 14 is positioned, and extends to a point where it connects with the contact member 43 which is in circuit with the contact members 31 of the innermost line of contact members 31.

10 The return circuit for the various contact members, is completed through the member 44 and wire 45, the member 44 being in circuit with the wire 34. In playing the game, the switch member 35 is operated to complete the circuit 15 to the various contact members arranged on the supporting plate 28. The disk 17 is now rotated by the operator grasping the finger piece 18 and giving the disk a slight rotary movement. As the disk rotates, the arm 21 moves with the 20 post 29, with the result that the contact members 25, 26 and 27, roll over the stationary contact members of the supporting plate 28.

When the disk ceases to rotate, the circuit 25 between adjacent stationary contacts, or the contacts over which the contact members 25, 26 and 27 rest, will be brought into the circuit, lighting certain of the lamps 14.

It is obvious that when the contact members 25 and 26 come to rest over contact members 30 which are in the outer and adjacent circular paths of the plate 28, the circuit to the blue and white lamps will be completed, causing the lamps to glow. Since twenty points are counted when the white lamp is lit, and thirty points are 35 counted when the blue lamp is lit, the scoring for this turn of the disk, will be fifty points.

The next player spins the disk, and when the disk comes to rest, the contact member of the plate 28 which is engaged by either of the contact members 25, 26 or 27, will cause a predetermined lamp to be lighted. When the contact member 27 comes to rest over the contact member of the inner line of contact members on the supporting plate 28, the red lamp will glow, 45 indicating ten points for the player.

If the contact members 25, 26 and 27 come to rest over the contact members in the group of three contact members, the person operating the disk will be credited with sixty points, ten for the

red lamp, twenty for the white lamp, and thirty for the blue lamp.

The number of points necessary to win the game may be decided by the players, and the person first to gain the number of points decided on, is judged the winner. 5

I claim:

1. A chance game device comprising a base, an insulated supporting disk mounted on the base, curved contact members arranged in groups 10 of various members, on the supporting disk, a source of electricity supply, a plurality of distinctive colored lights, an electric circuit between the contact members, source of electricity supply and lights, a ground circuit common to all 15 of said contacts, a post rising from the base and mounted for rotary movement thereon, a pivoted arm carried by said post, rotary contact members mounted on the arm and adapted to move over the contacts of the groups as the post is rotated, completing circuits to certain of said lights with each rotation of said rotary post, and said contacts adapted to complete a circuit 20 and maintain the circuit closed for a predetermined period of time when the rotary contacts 25 come to rest on certain of the stationary contact members.

2. A game device comprising a base, an insulated supporting disk mounted on the base, curved stationary contact members arranged in 30 groups of various numbers, on the supporting disk, a source of electricity supply, a plurality of distinctive colored lights, an electric circuit between the contact members, source of electricity, supply and lights, a ground circuit common to all 35 of said contacts, a post rising from the base and mounted for rotary movement thereon, a pivoted arm carried by said post, said arm having a horizontally disposed lower end movable over the supporting disk, rotary contact members mounted on the horizontally disposed end of the arm and adapted to move over the contacts of the groups, completing circuits to certain of said lights with each rotation of said rotary post, and said contacts adapted to maintain a circuit or 40 circuits closed for a predetermined period of time, when the rotary contacts come to rest on the stationary contact members. 45

GEORGE D. GIBSON.
